UNITED STATES PATENT OFFICE.

JOHANN JACOB FRIEDRICH STOCK, OF MUNICH, GERMANY.

DEVICE FOR CLEANING AND SMOOTHING FILMS AND THE LIKE.

Application filed June 17, 1926, Serial No. 116,677, and in Germany March 30, 1926.

This invention relates to devices for mechanically cleaning and smoothing cinematographic films and the like when they have become rough in use. The main object of 5 the invention is to provide a new means for film treatment embodying an improved process whereby heating, buckling, and breaking of the film, such as experienced with the hitherto known mechanical treatments, is successfully avoided and an effective cleaning and smoothing is attained without the material of the film being in any way affected.

Another object of the invention is the provision of means permitting an even tensioning of the film during its passage through the cleaning and smoothing device, and to give notice to an attendant in case of a disturbance occurring in the working of 20 the machine.

These and other objects of the invention are accomplished mainly by the provision of and treatment with metallic rotary brushes arranged within special cleaning cases and 25 over which the film is passed under the tension effected by weighted rollers which are loosely inserted in depending loops of the film at each side of the metallic brush or brushes.

30 The accompanying drawings illustrate the invention by way of example.

Fig. 1 is a part-sectional side elevation of one form of improved film cleaning and smoothing device embodying the invention,

35 Fig. 2 is a cross section through the centre of Fig. 1.

Fig. 3 shows a modified form of device having a number of cleaning cases and brushes at each side; and Fig. 4 illustrates 40 a wiring diagram for an electrical alarm arrangement.

In said drawings, the letter *a* denotes a machine casing which in the form shown has the shape of a box or cupboard and which is 45 accessible by doors or shutter *b*. Within the casing *a*, an electric motor *c* is arranged, while on its top, unwinding and winding-up drums or reels *d* and *e* are shown mounted to extend beyond the end walls of the 50 casing. The winding-up drums *e* are rotated by the electric motor *c* over a counter-shaft arrangement which will be more specifically referred to hereinafter.

Upon a shaft *f* which extends through the 55 machine casing, circular brushes *o* are arranged one at each side wall of the casing,

said brushes being driven at high speed by the electric motor *c*. Said brushes are of a width and curvature conforming to the width and curvature of the film to be 60 cleaned, and the brush wires are preferably made of a metal such as German silver which has good heat conducting qualities and is less expensive than other suitable materials. Each brush is shown enclosed 65 within a pocketlike side casing *g* closed tightly all round except near its upper end where a gap or slot is left free at each side thereof for the film to pass through. Owing to the fact of a brush being provided 70 at each side of the apparatus, one of said brushes may be used for the treatment of the picture-carrying layer of a film while the other brush on the side may be of a correspondingly finer texture and serve for the 75 treatment of the picture or emulsion side of the film.

From a shaft *x* carrying the film transport rollers *i*, the shafts *k*, *k'* for other transport rollers *m* and *n* are driven by means of 80 an intermediate gear *h*, a worm and worm wheel arrangement being used by preference as shown in Fig. 2 of the drawings.

When the device is working the film passes from the supply or unwinding reel *d* over the transport roller *m* and, by forming a downwardly depending loop around and upward again from an idling roller *r* past and in contact with the wire brush *o*, over the central transport roller *i*, down again along and in contact with the other side of the brush and finally, by forming a second loop around another idling roller *r* over the transport roller *n* onto the winding-up drum *e*. In the example shown, the 90 winding-up drums *e* are driven in a known manner by means of friction clutches *p* from the ends of the shafts *k* and *k'* respectively. While passing the brush *o*, the film preferably moves in the same direction with the 95 brush, and the working contact between the two is maintained by the idling rollers *r* yieldingly movable along guide slots *s* formed in the casing *a* at each side of the brush and serving as tension regulating 100 weights in a manner which is not new per se. Said roller-weights are obviously capable of up and down movement with their axles guided in said slots in the machine casing.

110 An electrical circuit may be arranged in connection with the device, embodying con-

tacts 1 and 2 located at the upper and lower ends of the slots *s* so that in event of disturbance in or interruption of operation, when the tension of the film becomes excessively loose or tight, the roller *r* would press against one or the other of the respective associated contacts as shown at the bottom right-hand corner of Fig. 4, and close the circuit through an alarm buzzer or bell 3 or 10 the like connected in the circuit with the wires 4 and 5. Obviously, if desired, the electrical circuit may be employed to automatically stop the machine rather than merely to sound an alarm.

15 The lower portion of each of the side casings *g* is formed as a closed container *t* for the reception of a cleaning liquid, such as methylated spirit, petrol, or the like.

The invention obviously is not limited to 20 the example shown in Figs. 1 and 2 of the drawings, because the manner and means of guiding the film through the apparatus may be varied, or the arrangement of the cleaning cases *g* or the driving means may be subject to alteration or modification. Also the 25 number of cleaning places (as represented by the number of brushes *o*) may be increased as desired or to suit special requirements. For example, two, three or more 30 brushes *o* with cooperable parts may be provided at each side of the machine as indicated in Fig. 3, in which three cases *g*¹, *g*², and *g*³ containing three wire brushes *o*¹, *o*² and *o*³ are provided at each side of the 35 main casing.

The chief technical advantage of the invention rests in the prevention of undue heating of the films. The metallic wires of 40 the brushes being excellent conductors of heat, immediately take up the heat from the film and pass it onto the surrounding air which is kept in constant circulation by the rapidity of the brush rotation. Thus a film treated by the improved method can not be 45 come unduly heated even if it bears upon the rotating brush with a comparatively strong pressure.

What I claim is:—

1. A device for cleaning and smoothing 50 worn films and the like, comprising a machine stand, a metallic wire brush rotatably arranged upon the machine stand, means to move the film past and in contact with the said wire brush, and means to exert a con-

stant co-operative pressure between the film 55 and the said brush.

2. A device for cleaning and smoothing films and the like, comprising a machine stand, a closed casing on the machine stand, a metallic wire brush rotatably arranged 60 within the casing, a slot in the casing for the film to pass through in peripheral contact with the wire brush, transport pulleys to feed the film from the reels past the said wire brush, and weighted rollers loosely arranged in depending loops of the film before and after the said brush and adapted to exert a self-regulating pressure of the film 65 against the brush.

3. A device for cleaning and smoothing 70 films and the like, comprising a main casing serving as a machine stand, a driving motor within the said casing, a closed casing outside the main casing, a metal wire brush rotatably arranged in the side casing, a shaft for 75 rotating the said wire brush passing through the main casing and driven from the electric motor within the said casing, slots in the side casing for the film to pass through in peripheral contact with the wire brush, fast 80 transport rollers driven from the electric motor over a countershaft arrangement, loose weighted rollers each inserted in a loop formed in the film before and after the wire brush, and slots in the side walls of the 85 main casing to guide the axles of the loose weighted rollers during any up and down movement caused by the moving film.

4. A device for cleaning and smoothing 90 worn films and the like comprising a machine stand, metallic wire brushes rotatably arranged on the machine stand, means for moving a film past and in contact with the said wire brushes, weighted rollers loosely 95 inserted in depending loops of the film and adapted to exert a self-adjusting constant pressure between the film and each of the said metallic wire brushes, slots to guide the axles of the said weighted rollers, electric contacts near the ends of the said slots 100 adapted to be closed by the weighted rollers when the film becomes excessively slack or tight, and an electric device in the circuit of the said contacts to be actuated upon the closing thereof.

In testimony whereof I affix my signature.

JOHANN JACOB FRIEDRICH STOCK.
